UNITED STATES PATENT OFFICE

154,052

DESIGN FOR WRAPPING PAPER

Oswald F. Marquardt, Montclair, N. J.

Application June 17, 1947, Serial No. 139,737

Term of patent 7 years

(Cl. D59—2)

To all whom it may concern:

Be it known that I, Oswald F. Marquardt, a citizen of the United States, residing at Montclair, in the county of Essex and State of New Jersey, have invented a new, original, and ornamental Design for Wrapping Paper of which the following is a specification, reference being had to the accompanying drawing, forming a part thereof.

The figure is a piece of wrapping paper showing my new design. The design unit is outlined by broken lines, and is repeated as indicated by the extension beyond the unit boundary.

I claim:

The ornamental design for wrapping paper, as shown and described.

OSWALD F. MARQUARDT.
